UNITED STATES PATENT OFFICE.

HAVY Q. R. CROWDER, OF CHICAGO, ILLINOIS.

ELLIPSOGRAPH.

1,373,056.

Specification of Letters Patent.

Patented Mar. 29, 1921.

Application filed May 5, 1919. Serial No. 294,895.

To all whom it may concern:

Be it known that I, HAVY Q. R. CROWDER, a citizen of the United States, residing at Chicago, in the county of Cook and State 5 of Illinois, have invented a certain new and useful Ellipsograph, of which the following is a specification.

The object of the present invention is to provide a device of the character named 10 which shall be of improved construction and operation.

The invention is exemplified in the combination and arrangement of parts shown in the accompanying drawing and described 15 in the following specification, and it is more particularly pointed out in the appended claims.

In the drawing—

Figure 1 is an elevation of an instrument 20 forming a part of the present invention;

Fig. 2 is a combined pen and pencil for use in connection with the instrument shown in Fig. 1 in drawing ellipses;

Fig. 3 is a perspective view showing the 25 manner in which the instruments shown in Figs. 1 and 2 are operated in drawing an ellipse;

Fig. 4 is a sectional view showing the 30 spring spool for holding the cord which forms a part of the instrument shown in Fig. 1; and

Fig. 5 is an enlarged detail showing a 35 spring clip which forms a part of the invention.

It frequently occurs in the preparation of drawings of various kinds that it becomes necessary for the draftsman to describe ellipses, and in some kinds of work it is desirable that these ellipses be accurately 40 drawn and that they conform to specified dimensions. The present invention provides an ellipsograph which, although simple and easy to adjust and operate, will accurately produce ellipses conforming to prescribed 45 dimensions.

In Figs. 1 and 3 of the drawing, the numerals 10 and 11 designate the arms, respectively, of an instrument made on the general plan of a pair of dividers, but especially 50 constructed and equipped for the particular purpose of this invention. The arms 10 and 11 are pivoted together at 12 so that they are frictionally held in the various positions to which they may be opened. The 55 extremities of the arms 10 and 11 carry pointed extensions 13 and 14, respectively,

the extensions being pivoted to the ends of their arms at 15 and 16, respectively. The pivot screws 15 and 16 are provided with wing nuts 17 and 18 which may be tightened 60 to hold the extensions 13 and 14 in various angular positions of adjustment relative to the arms 10 and 11. The arm 11 is provided with a bracket 19 on which is journaled a spool 20. The spool 20 is provided 65 with a spring 21 for rotating the spool to wind a cord 22 thereon. As shown more clearly in Fig. 5, a circumferential groove 23 is formed on the lower end of the extension 14, and the lower jaw of a spring clip 24 is pivoted in the groove thus formed. The upper jaw on the spring clip 24, as shown in Fig. 3, is provided with an opening 25 through which the extension 14 loosely passes, and a smaller opening 26 near 75 the outer end of the upper jaw permits the passage of the cord 22 therethrough. This arrangement brings a portion of the cord between the jaws of the spring clip so that the cord is frictionally held by the clip. 80 The end of the cord 22 is secured to a flattened ring 27 pivoted on the lower end of the extension 13 in a groove similar to the groove 23 on the extension 14. The openings through the ring 27 and the lower jaw 85 of the spring clip 24 are small enough so that these parts are retained in place in the grooves surrounding their respective supports. The points on the extensions 13 and 14, below the ring 27 and spring clip 24, 90 are of substantially the same length, so that when the pointed ends of the extensions are placed upon a sheet of paper, or other surface, the cord 22 will extend above the surface and parallel therewith. 95

The drawing instrument shown in Fig. 2 is provided with a handle portion 28, one end of which carries a clip 29 for holding a short length of lead, or other drawing material 30. The opposite end of the handle 100 28 is provided with a ruling pen 31 for drawing with ink. The clip 29 and the ruling pen 31 are both provided with shoulders 32 which extend entirely around the rods 33 by which the drawing points are connected with the handle 28. The drawing points 29 and 31 are made of a proper length to bring the shoulders 32 at a height above the surface being operated upon equal to the height at which the cord 22 is held 110 by the ring 27 and the spring clip 24.

The upper ends of the extensions 13 and

above the plate adapted for engagement by the article to be pressed when the plunger is moved upwardly, and means for raising and lowering the plunger comprising pipes 5 communicating with the cylinder and disposed beneath the floor, one pipe serving to admit fluid under pressure and the other serving to exhaust the same, a check valve

in the inlet pipe, control valves in both pipes, and means for operating the control valve comprising a pedal pivoted on the floor, an arm carried by the valve stem, and a rod passing through the floor and connected with the pedal and said arm.

JAMES ANDREW COHILL.

- 5 pivotally mounted on each of said supporting members, means for holding said elongated members against pivotal movement on their supporting members, and a cord for 60
 5 guiding a line tracing instrument arranged to extend from one of said elongated members to the other, said cord having one end thereof attached to one of said pointed members, and means for adjustably securing 65
 10 the other end of said cord to the other of said pointed members.
4. In combination, a pair of supporting members adjustable toward and away from one another, an elongated pointed member 70
 15 pivotally carried by each of said supporting members, means for indicating when said elongated members are arranged in parallel relation relative to one another, means for holding said elongated members 75
 20 in fixed position on said supporting members, and a cord connected with each of said elongated members adjacent the pointed end thereof for guiding a line tracing instrument.
- 25 5. In a drafting instrument, a pair of supporting members adjustable toward and away from one another, an elongated pointed member pivotally mounted on each of said supporting members, and an external shoulder on each of said elongated members arranged to coöperate with a straight edge for 80
 30 setting said elongated members in parallel relation relative to one another when said shoulders are brought into alinement with 85
 35 one another.
6. In a drafting instrument, a pair of supporting members adjustable toward and away from one another, an elongated pointed member pivotally carried by each of said 90
 40 supporting members, a shoulder connected with each of said elongated members for co-operating with a straight edge to arrange said elongated members in parallel relation relative to one another, and means for holding 95
 45 said elongated members against pivotal movement on said supporting members, said elongated members having indicating marks thereon to assist in setting the points of said members at a predetermined distance 100
 50 from one another.
7. A drafting instrument comprising a pair of supporting members pivotally connected to one another at one end thereof, elongated pointed extensions pivotally carried on the free ends of said supporting members, T-heads on said extensions adja- 105
- cent the pivots thereof, said T-heads being arranged to provide shoulders for coöperating with a straight edge to set said extensions in parallel relation relative to one another, means for holding said extensions against pivotal movement on said supporting members, said T-heads having indicating marks thereon adjacent said shoulders to assist in setting the points of said extensions at a predetermined distance from one another, and a cord having opposite portions thereof connected with said extensions adjacent their pointed ends and arranged to guide a line tracing instrument held against said cord.
8. A drafting instrument comprising a pair of spaced members, a cord having one end thereof connected with one of said members, a spring clip connected with the other 75
 85 of said members and frictionally and resiliently engaging said cord to hold said cord in fixed position relative to said member during a drafting operation but arranged to permit movement of said cord 80
 when sufficient force is applied thereto for adjustment of said cord.
9. A drafting instrument comprising a frame having spaced members thereon, a cord for guiding a marker having one end 90
 95 thereof connected with one of said members, a spring clip for yieldingly holding said cord in connection with the other of said members, and a take-up device for holding the portion of said cord on the side of said spring clip away from the portion thereof which acts as a guide for said marker.
10. An ellipsograph comprising a pair of arms pivotally connected to one another at one end thereof, pointed members pivoted 95
 100 to the opposite ends of said arms, means for maintaining said pointed members in parallel relation to one another, a device pivotally mounted on one of said pointed members in spaced relation relative to the end thereof and arranged to swing about the axis of said pointed member, a cord connected with said pivoted device, a spring clip pivotally mounted on the other of said pointed members and arranged to frictionally engage said cord, and a spring take-up 105
 for holding excess portions of said cord.

In testimony whereof I have signed my name to this specification on this 1st day of May A. D. 1919.

HAVY Q. R. CROWDER.
